UNITED STATES PATENT OFFICE.

SAMUEL BERGSTEIN, OF MIDDLETOWN, OHIO, ASSIGNOR TO THE INTERSTATE FOLD-
ING BOX COMPANY, OF MIDDLETOWN, OHIO.

PAPER-BOX-MAKING MACHINE.

Application filed June 25, 1924. Serial No. 722,330.

To all whom it may concern:

Be it known that I, SAMUEL BERGSTEIN, a citizen of the United States, residing in Middletown, in the county of Butler and 5 State of Ohio, have invented certain new and useful Improvements in Paper-Box-Making Machines and the like, of which the following is a specification, reference being had therein to the accompanying drawings. 10 This invention relates to paper box making machines, having particular reference to a new type of semi-automatic machine comprising features of construction and operation broadly new in the art to which the 15 invention relates.

The main object attained in the invention is a semi-automatic box making machine of simple construction, that can be manufactured in quantities at relatively low cost, 20 that will have a wide range of adaptation for making boxes of improved construction, of different styles and sizes, and which will have a relatively large production capacity on small quantity orders.

Under present practices in the box manufacturing industry, with and without the use of automatic machinery, small quantity orders cannot be handled economically, the time and labor cost of hand-made boxes, and 30 the job setting operations and details involved in preparing the stock for automatic machinery on small orders being conditions which preclude the possibility of low cost production.

Small quantity orders for special shapes and sizes of boxes constitute a large percentage of the business of paper box manufacturers and, therefore, an important phase of the industry. Thus the importance of improved machinery which will be effective 40 to increase and cheapen production, and at the same time effective also to improve the product structurally will be appreciated by those informed as to the needs of the industry.

A feature of the invention consists in adapting a new type of gluing mechanism to semi-automatic box making machinery whereby to effect better construction of the 50 glued joints as the boxes are formed on the machine. The improved glue applying mechanism as herein shown and described in modified form to meet the requirements of the new machine, is substantially the same 55 in principle as that set forth in my copend-

ing application for patent Serial No. 664, 415 filed Sept. 24, 1923.

A further feature of the invention consists in the adaptation of high-pressure mechanism, in conjunction with the glue applying 60 mechanism, to effect a firm adhesion, one part with another of the box blanks, at the joints to overcome the faulty, open-joint construction of boxes made by hand or with unsuitable machinery.

A feature of the invention consists in means provided for regulating the joint pressure mechanism to the thickness of the stroke, or the number of folds of the stock 70 at the joints in order that uniformity of the applied processes of production as well as in the quality of the product can be maintained.

A further feature of the improved machine consists in means provided for making 75 the body and lid portions of two-piece boxes, when the same are of different sizes to permit of one telescoping the other, without making material changes in the set-up of the machine.

These main features, together with the mechanical organization and coordinated operation of the machine, as illustrated in the accompanying drawings, described in detail in the following specification and defined 85 and comprehended in the appended claims, I believe to be broadly new in the art to which my invention pertains. It will be obvious to those skilled in the art that various modifications and adaptations of the 90 underlying principle of the machine, as herein set forth, can be made without departing from the principle of the invention.

In the drawings:

Fig. 1 is a side elevation of the machine. 95

Fig. 2 is a detail side elevation of the machine taken at right angles to Fig. 1;

Fig. 3 is a sectional view of the machine taken on line 3—3 of Fig. 2;

Figs. 4 and 5 are detail views of the actuating mechanism for the machine work table.

Fig. 6 is a detail view illustrating a type of box adapted to be made on the improved machine.

The complete machine, as shown in Fig. 1, is supported on a hollow column 1, which is tapered and externally threaded at its upper end as at 2, and the end of the column being slotted at intervals of 90° as at 3, and 110

provided with a clamp band 4. A machine head 5 having a downwardly extended portion 6 is mounted telescopically on column 1, being held in fixed relation therewith by means of the clamp band 4. A work table 7 is mounted rotatably on portion 6 of the machine head 5 and is adapted to be adjusted vertically relative thereto by means of an adjusting band 8, threaded onto part 6 10 as at 9 for a purpose which will presently be described.

The machine head comprises a power belt wheel or tight-and-loose pulley 10 mounted on a drive shaft 11 supported in bearing 12, 15 the opposite end of the shaft being operably connected to a ram 13 by means of a crank connection 14 of the usual construction. Ram 13 comprises a head 15 at its lower portion and an upwardly extended portion 16 retained in vertical sliding relation on the machine head by means of guides 17 fastened on the vertical face of the head by bolts 18, the crank connection 14 being made between shaft 11 and part 16, the same being covered by a face plate 19 secured to part 16 by means of screws 20.

Also supported on the machine head by means of a bracket 21 and screws 22 are compounded levers 23-24, joined one to the other at their adjoining ends by a link 25, lever 23 being connected to part 16 of the ram 13 as at 26 and pivoted in bracket 21 as at 27. Lever 24 is pivoted on the machine head as at 28 and is provided at its lower end 30 with a sleeve bearing 29 adapted to sustain operative relation between the lever and a pawl carrying plate, comprising a sleeve portion 30 and a laterally extended, bifurcated portion 31, mounted to be actuated reciprocally, horizontally on the downwardly extended portion 6 of the machine head by the lever 24. Plate 30-31 is provided on the under side thereof with a pawl 32 operatively connected with a ratchet gear 33 which in turn is rigidly secured on the upper face of the work table 7 concentrically of part 6 of the machine head. By the arrangement of the parts described it will be seen that upon each stroke of the ram 13 the work table 7 will be rotated, the extent of rotation as provided in the described construction being 90° upon each reciprocation of the ram.

Also connected to part 13 of the ram mechanism by means of a laterally extended arm 34 and downwardly depending arms 35, is the gluing mechanism, 36, which as here shown comprises the glue container 37, the port closing stems 38 with their spring pressure devices 39. The details of construction of the container and glue applying mechanism being fully described in my copending application for Letters Patent thereon herein referred to.

No novelty is claimed relative to the glu-

ing mechanism except in combination with other elements of the machine which are co-ordinated therewith in functions of operation of the machine as a whole.

The gluing mechanism and the joint forming mechanism—ram 13—are actuated reciprocally by means of the crank connection 14 between part 16 and shaft 11, the belt wheel 10 being keyed to the shaft in the usual manner of tight-and-loose pulleys and controlled in its idle and operative relation therewith by a bolt 40 connected to a treadle 41, mounted on the base of the machine, by a link 42.

The work table 7, as herein described, is adapted to be rotated one step—90°—upon each stroke of ram 13 and the gluing mechanism 36. The table comprises a plurality—four as here shown—of work supporting heads 43 adapted to have a partially folded box positioned thereon by the attendant of the machine.

To retain the boxes in position on the work heads each head is provided on the opposite sides thereof with spring clips 44 which are arranged at their free ends, which project outwardly, to receive opposite sides of the box edgewise between the springs and the adjacent edges of heads 43, the tension of the springs serving to exert sufficient pressure on the boxes to hold the same firmly in position thereon as the boxes are moved through the successive operations of forming the glued joints thereof.

Also associated with the work heads 43 are folding elements 45 which serve to fold the end flaps of the box as the same is moved to position on the work heads, as shown in Fig. 3, the box being shown in dotted outline, the folded ends then passing under the guard 46 which is arranged circumferentially of the machine, and serves to hold the end of the box in folded relation for the successive operations of applying the glue to the end flaps and forming the joints as the same are acted on by ram 13.

As shown in the detail view of Fig. 3 the direction of rotation of work table 7 is clockwise, the boxes with their sides folded at right angles to their bottoms and end flaps extended, being put on the work heads 43 by the attendant of the machine, the end flaps *a* of the box being partially folded by hand as the box is positioned on the work head, the folds being completed as the flaps are moved under the folding members 45. Upon operation of the foot lever 41, the power wheel 10 will be brought into driving relation with shaft 11 and a complete reciprocation of the gluing and joint forming mechanisms will take place—the work table being rotated a quarter turn on the up or idle stroke of the ram.

The successive steps of operation of the machine, as herein shown, are indicated in

Fig. 3 as A, B, C, D. In the A position the boxes are put on the work supporting heads manually by the attendant. On the first quarter turn of the work table the same are 5 moved to B position which is an idle position; on the second quarter turn the boxes are moved to C position where glue is applied to the end flaps; on the third quarter turn the boxes are moved to D position 10 where the glued joints are formed under high pressure exerted on the folded ends of the box under the ram; on the fourth quarter turn of the work table the boxes are again brought to A position and are reversed end 15 for end by the attendant and replaced on the work heads for the second time around to effect similar operations on the opposite end of the box. With both ends of the box glued, the same are removed from the work 20 head by the attendant and replaced thereon with another box.

To adapt the work supporting heads 43 for gluing both units of telescopically arranged boxes, work heads 43 are rectangular 25 shaped but not square, the difference in dimension of length and width being sufficient to correspond to the difference of width between the top and bottom of the box to permit one to telescope the other. For 30 the same reason the work heads are detachably mounted on the work table and are provided on their under sides with a pilot 47 and a dowel 48 and each of the radially extended arms of the work table with a pilot 35 hole 49 and two dowel holes 50, one of the dowel holes of each arm being occupied as shown in Fig. 3 by a dowel 48 which serves to hold the plate in position on the arm. To adapt the work heads for supporting one 40 or the other of the different units of the box—top or bottom—the heads are placed on the work table with dowel 48 in register with one or the other of holes 50 as desired. It will be obvious that work heads of different 45 sizes can be used on the machine, and thus that the machine has a wide range for different size boxes. When the heads 43 are changed to positions at right angles to that shown the folding elements 44 will be retained in the relation shown.

The four work heads with which the machine is provided as herein shown and described merely serve to illustrate the principle of construction and operation of the 55 machine. A greater or less number can be used as may be desirable for different styles and sizes of boxes, and other gluing and forming operations and automatic or semi-automatic mechanisms can be provided for 60 on the machine without departing from the principle and spirit of the invention.

To accommodate the position of guard wire 46 over the box supporting head, as shown in Fig. 3, a clearance space is provided 65 on the under side of head 15 of the

ram as indicated at 49^a in Fig. 1. It will be obvious that the guard wire 46 is not continuous over the work supporting head in positions A and C and that in each of these positions the folding elements 45 and 45^a are 70 provided to fold the end flaps, parts 45 acting to fold the opposite side flaps *a*, which receive the deposit of glue thereon, as the boxes are positioned on heads 43, and part 45^a to fold the bottom flap *b* over the side 75 flaps after the glue has been applied thereto, and thus to cause a glued joint to be formed as the box comes under the pressure of ram 13.

From the foregoing description and the 80 accompanying illustrations of the drawings the construction and operation of the machine as a whole will be readily understood.

Having described my invention, I claim:

1. A box making machine including in combination with gluing and joint forming mechanism operably supported on said machine, a plurality of box supporting units, means coacting with each unit to effect a fold on a box as the same is positioned thereon, said units being adapted to be moved successively into operative relation 90 respectively with said joint forming and gluing mechanisms whereby upon operation of the same a glued joint of said box 95 will be effected.

2. A box making machine including in combination with gluing and joint forming mechanism operably supported on said machine, a plurality of box supporting units, means coacting with each unit to effect a fold on a box as the same is positioned thereon and to support the fold as said units are moved successively into operative relation 100 respectively with said joint forming and gluing mechanisms whereby upon operation of the same a glued joint of said box 105 will be effected.

3. A box making machine including in combination with gluing and joint forming mechanism operably supported on said machine, a plurality of box supporting units each adapted to have a box positioned thereon releasably, and reversibly as to opposite ends of the box, said units being adapted to be moved successively into operative relation with said gluing and joint forming mechanism whereby upon operation of the same a glued joint of said box will be effected.

4. A box making machine including in combination with gluing and joint forming mechanism, a plurality of box forming units adapted to be moved into operative relation with said mechanisms, means associated with each unit to effect a fold on a box as the same is positioned thereon, means interposed between said units adapted to hold the folded portion of the box in said relation as said units are moved into said opera- 125

130

tive relation, whereby upon operation of said mechanisms a glued joint will be effected on said box.

5. A box making machine including in combination with gluing and joint forming mechanism, a plurality of box forming units adapted to be moved into operative relation with the said mechanisms, means associated with each unit to effect a fold on a box as 10 the same are positioned thereon, means to retain a box in said position, and means to hold the folded portion in said relation as said units are moved into said operative relation with the gluing and joint forming 15 mechanisms, whereby upon operation of said mechanisms a glued joint will be effected on said box.

6. A box making machine including in combination, gluing mechanism and joint forming mechanism operable reciprocally simultaneously one with the other in vertical planes spaced one from the other, a rotatable member operable in a horizontal plane and comprising a plurality of box carrying units adapted to be moved upon actuation of said member in a path intersecting the planes of operation of said mechanisms and to be brought to a position with one unit in operative relation with 20 the gluing mechanism and another unit in operative relation with the joint forming mechanism, whereby upon transmitting operating movement to said mechanisms the same will be actuated simultaneously and a 25 deposit of glue will be made on a box on one of said units and a glued joint will be formed on the other of said units.

7. A box making machine including in combination, gluing mechanism and joint forming mechanism operable reciprocally in unison one with the other, a plurality of box supporting units operable in unison step by step in a continuous path intersecting the planes of operation of said mechanisms to 30 positions of rest, with one unit in operative relation with said gluing mechanism and another unit in operative relation with said joint forming mechanism, whereby upon one stroke of said reciprocal movement a deposit 35 of glue will be made on a box aligned with the gluing mechanism and a glued joint will be formed on another box aligned with the joint forming mechanism, and upon the other stroke of said reciprocal movement 40 said aligned units will be moved out of said operative relation and other box supporting units will be moved into said gluing and joint forming relations.

8. A box making machine including in combination, gluing mechanism and joint forming mechanism adapted to be actuated reciprocally, a work table operable rotatably and comprising a plurality of box supporting units adapted to be moved thereby successively into positions of rest in operative 45

relations with said mechanisms, means provided in one of said positions to fold portions of a box as the same is placed on a box supporting unit, and means arranged along the path of said units acting to retain the folded portions of the box in said relation as the same are moved into said operative relations with the gluing and joint forming mechanisms whereby upon operation of said mechanisms a deposit of glue 50 will be made on the folded portions of one box and a glued joint will be formed at the folded portion of another box supported on said units.

9. A box making machine including in combination, reciprocally operable gluing and joint forming mechanisms, a rotatable work supporting member having a plurality of mechanisms thereon adapted to support a box and to effect a fold of portions thereof as the same is placed thereon, means to actuate the work table step by step whereby each of said work supporting mechanisms will be brought successively into operative relation with the gluing and joint forming mechanisms, a guard arranged along the path of rotation of the work supporting mechanisms acting to hold the ends of the box in folded relation as the same are moved from one to the other of said operating positions, whereby upon actuation of said mechanisms gluing and joint forming operations will be effected successively on a box and simultaneously on 60 boxes supported on different units of said mechanisms.

10. A box making machine including in combination, reciprocally operable gluing and joint forming mechanisms, a rotatable member adapted to be operated step by step and comprising a plurality of work supporting units each adapted to support a box and means associated therewith to fold parts of a box as the same is placed thereon, said units being adapted to be moved successively to a position to so receive a box, thence into operative relation with the gluing mechanisms, and thence into operative relation with the joint forming mechanism, means associated with the joint forming mechanism acting to fold additional portions of the box over said first-folded portions whereby upon actuation of said machine glued joints of 65 said folded portions of the boxes will be effected.

11. A paper box making machine including in combination with a machine head, gluing and joint forming mechanisms operable reciprocally in a vertical plane in unison one with the other on said head, a work supporting table operable rotatably in a horizontal plane below the plane of operation of said mechanism, and comprising a plurality of box supporting members adapted to be moved successively into operative 70

relations with said mechanisms, whereby to form glued joints on boxes supported on said members, different units of the box supporting members being adapted to be moved simultaneously into operative relation with the respective mechanisms.

12. A paper box making machine including in combination with a machine head, gluing and joint forming mechanisms operable reciprocally in a vertical plane in unison one with the other on said head, a work supporting table operable rotatably in a horizontal plane below the plane of operation of said mechanism, and comprising a plurality of box supporting members each having means associated therewith to effect folds on boxes placed thereon, and adapted to be moved successively into operative relations with said mechanisms, means arranged along the path of rotation of said members acting to retain said folds and to effect additional folds whereby to form glued joints on boxes supported on said mechanisms.

13. A paper box making machine including in combination with a machine head, gluing and joint forming mechanisms operable reciprocally in a vertical plane in unison one with the other on said head, a

work supporting table having a step by step 30 operative relation with the reciprocal movement of said mechanisms, adapted to be actuated rotatably in a horizontal plane thereby, and comprising a plurality of box supporting members adapted to be moved 35 successively into operative relations with said mechanisms, whereby to form glued joints on boxes supported on said mechanism.

14. A paper box making machine including in combination with a machine head, gluing and joint forming mechanisms operable reciprocally in a vertical plane in unison one with the other on said head, a work supporting table operable rotatably in 45 a horizontal plane below the plane of operation of said mechanism, and comprising a plurality of box supporting members adapted to be moved successively into operative relations with said mechanisms whereby to 50 form glued joints on boxes supported on said members, and means to adjust the work table vertically to compensate for variations of the paper stock and in the folded portions of the boxes for effecting said glued joints. 55

In testimony whereof, I affix my signature.

SAMUEL BERGSTEIN.
